United States Patent Office.

C. C. GISH, OF VIRDEN, ILLINOIS.

Letters Patent No. 64,661, dated May 14, 1867.

IMPROVEMENT IN WINDMILLS.

The Schedule referred to in these Letters Patent and making part of the same.

TO ALL WHOM IT MAY CONCERN:

Be it known that I, C. C. GISH, of Virden, in the county of Macoupin, and State of Illinois, have invented a new and improved Wind-Power; and I do hereby declare that the following is a full, clear, and exact description thereof, which will enable others skilled in the art to make and use the same, reference being had to the accompanying drawings forming part of this specification.

This invention relates to a new and improved wind-power, designed for pumping water, and it consists of a wind-wheel constructed in a novel manner, and arranged in connection with a pump, tank, and a receiver, provided with a valve, with a float attached, and connected with a lever by which the wings of the wind-wheel may be opened and closed automatically. In the accompanying sheet of drawings—

Figure 1 is a side view of my invention.

Figure 2, a horizontal section of the same, taken in the line *x x*, fig. 1.

Similar letters of reference indicate like parts.

A represents a framing, which may be constructed in any proper manner to support the working parts, and B is a shaft placed vertically in said framing, and having a wind-wheel, C, secured on its upper end. This wind-wheel is composed of two horizontal circular plates *a a*, between which radial partitions *b* are placed to form chambers *c*, as shown clearly in fig. 2. The upper plate *a* is solid throughout, but the lower one has a circular opening, *d*, at its centre, through which the wind escapes from the chambers *c*. To the outer edge of each partition *b* there is hinged a wing, *d*, and these wings, when closed, cover the outer ends of the chambers *c*, and in consequence do not present any surface to the action of the wind, nor allow any wind to enter the chambers *c*, the wind-wheel being therefore inoperative. These wings *d* are connected by rods *e* with a sliding hub, D, on the shaft B, and this hub D is connected by rods *ff* with a similar hub, E, on the shaft B below the wind-wheel. The hub E has a groove made circumferentially in it to receive a loose ring, *g*, which is attached to an upright, F, the lower end of the latter being pivoted in a lever, G, which has its fulcrum in an upright, *h*, attached to the base of the framing A. On the wind-wheel shaft B there is also keyed an eccentric, H, which is connected by a metallic strap with a bar, I, having its outer end pivoted to the upper end of a bent lever, J, to the outer end of the lever-arm of which the piston-rod, *j*, of a pump, K, is connected. L is a water-receiver, one end of which is provided with journals, *k*, fitted in uprights *l*, the receiver near its upper end resting or bearing on the outer part of the lever G, said lever, near its inner end, having a weight, M, attached. In the bottom of the water-receiver L there is an opening, *m*, over which a valve, N, works. This valve is attached to one end of a bar, O, the opposite end of which is secured to a shaft placed transversely in the receiver, and having journals at its ends which work in the sides of the receiver. The bar O, directly over the valve N, has a cord or chain, *n*, attached, which passes over a pulley, *o*, secured to the framing, and is connected to a float, P, which works on a vertical guide-rod, *p*, within a tank, Q, placed on the base of the framing A, as shown in fig. 1. R is an eduction pipe which leads from the pump K upward into the water-receiver L.

The operation is as follows: In order to start the device the inner end of the lever G is pressed down, and the wings *d* are thereby forced outward, as shown in fig. 2, so as to present a surface to the action of the wind, and the wind-wheel will therefore be rotated and the pump K operated from the wheel-shaft B, through the medium of the eccentric and lever previously described, and water will be pumped up into the receiver L, and will pass through the hole or opening *m*, into the tank Q, the float P being sufficiently heavy to keep the valve N open. When the tank Q becomes full, the float P will rise and close the valve N, and the receiver L will then fill, and the weight of the water in L will depress the outer part of lever G, the inner part of said lever of course rising and causing the wings *d* of the wind-wheel to close, and the latter thereby rendered inoperative. When the water from the tank Q is drawn off, the gravity of the float P will raise the valve N, and cause the water in the receiver, L to be discharged into the tank, and the inner part of the lever G, through the influence of weight M, will overbalance the empty receiver L, and consequently will be depressed, and the wings *d* again thrown open, and the wind-wheel operated by the action of the wind.

The device is extremely simple and efficient, operating with certainty, and capable of being manufactured and put up for actual use at a very moderate cost.

Having thus described my invention, I claim as new, and desire to secure by Letters Patent—

1. A wind-wheel constructed substantially as shown, and provided with hinged wings *d*, and rods *e*, sliding hubs *D E*, arranged in relation with water-receiver *L*, and loaded lever *G*, substantially as shown and described for the purpose specified.
2. The float *P* in tank *Q*, the valve *N* in the water-receiver *L*, and the lever *G*, all arranged to operate in connection with the wind-wheel, substantially as described.

C. C. GISH.
